UNITED STATES PATENT OFFICE.

ALFRED G. HOLCOMBE, OF GRANBY, CONNECTICUT.

ELECTRIC LIGHT.

SPECIFICATION forming part of Letters Patent No. 233,096, dated October 12, 1880.

Application filed May 20, 1880. (No model.)

To all whom it may concern:

Be it known that I, ALFRED G. HOLCOMBE, a resident of Granby, county of Hartford, State of Connecticut, have invented certain 5 new and useful Improvements in Electric-Light Apparatus, of which the following is a specification.

This invention relates to electric-lighting apparatus; and it consists in the combination 10 of a small armature with a piece of soft iron, constructed and arranged to be controlled by the magnetic action of an electric current thereon, or by magnetic induction, and so connected to the carbon rods of the apparatus as 15 to keep the electric arc of the right length to give a light in proportion to the current, said small armature being controlled by the movement of the piece of soft iron, so as to always maintain its proper positions thereto, to be 20 acted on by magnetic induction therefrom, and to apply a clamp or brake to the feeding device which connects the carbon rods to the moving piece of soft iron, thus preventing the carbon rods feeding toward each other until 25 the arc has increased in length sufficiently to reduce the current and lower the magnetism of the moving piece of iron enough to admit of the small armature being retracted therefrom by a spring or weight, thereby opening 30 the clamp or brake to allow the feed to work.

There are several ways in which electric-lighting apparatus may be constructed to embody this principle; but the simplest way that is at present known to me consists of a vertically-placed axial magnet, the core of which is suspended from one end of a horizontal lever, and the other end is provided with a socket through which slides a vertical metal rod carrying the upper carbon. Pivoted to this lever, at a 40 point near the socket, is a light bell-crank or right-angled lever, the short arm of which presses against the metal rod to bind it tight in the socket of the main lever, and the long arm lies horizontally, so that its extreme end is over the core of the axial magnet, and to this end is adjustably fitted the small armature immediately over the upper end of the core of the axial magnet, in close proximity thereto, but adjusted so as never to come in contact 45 therewith, and the magnetic attraction between them is opposed by an adjusting-spring con-

nected to the long arm of the bell-crank lever and a projection from the main lever. The movement of the main lever, carbon rod and holder, and core of the axial magnet is governed, and the magnetic action of the current on the core opposed and regulated, by an adjusting-spring, one end of which is connected to the main lever and the other end to the frame of the apparatus, all of which will be 55 fully hereinafter described by reference had to the accompanying drawings, forming part of this specification, in which—

Figure 1 is a side elevation, partly in section. Fig. 2 is a front elevation, also partly 60 in section; and Fig. 3 is a plan view of the same.

My improvements in electric-lighting apparatus are shown in the drawings as applied to a bracket-lamp to be secured to a post or wall, 70 in which *a* represents the frame provided with attaching-ears *a' a'*.

The axial magnet *b* is secured in a vertical position to the frame *a*, and is provided at its upper end with a metal plate or head, *c*, projecting upwardly from which are the standards *c' c'*, and to these standards is pivoted 75 the lever *d*.

The lever *d* is slotted through its entire length, and one end of it is formed into a circle, the center of which is directly over the center of the axial magnet *a*, and to this end of the lever is secured, by means of the links *e e*, the core *e'* of the axial magnet, the lower end of the core having a guide-pin, *e²*, which 85 passes through a hole in the lower plate or head of the axial magnet to keep the core in a central position. The outer end of the lever *d* is provided with a socket, *f*, in which is fitted the rod *g*, so as to slide freely therein, and 90 the inner side of this socket is cut away to allow the short arm of the bell-crank or right-angled lever *h* to come in contact with the rod *g* when the long arm of it is depressed, and so clamp the rod *g* rigidly to the socket *f* at the 95 end of the lever *d*.

The rod *g* may be serrated or roughened, and the short arm of the lever *h* provided with teeth; but I prefer to make them both smooth.

The bell-crank lever *h* lies in the slot formed 100 through the lever *d*, and is pivoted thereto at a point near the socket *f*. The end of the long

arm of the bell-crank lever h is over the end of the core e' of the axial magnet, and it carries the small armature i , which has a screw-stem fitting in a tapped hole in the end of it, which

5 admits of the adjustment of the small armature i in its relation to the core e' , and when properly adjusted it is locked to the arm of the bell-crank lever by means of the thumb-nut i' .

The armature i is drawn away from the 10 core e' , and the short arm of the bell-crank lever h caused to release the rod g by means of the adjustable spring k , the upper end of which has a screw-stem which passes through a hole in the standard k' , secured to the lever d , and 15 the stop-pin k^2 prevents the spring k moving the lever farther than is necessary to just free the rod g to allow it to slide freely through the socket f . The upper carbon, l , is secured to the lower end of the rod g , and the lower 20 carbon, m , is held in a socket on the end of the arm n , which is secured to the lower end of the frame a by means of an insulating-connection.

To the inner end of the lever d is secured 25 one end of the spring o , the other end of which is provided with a screw-stem passing through a lug from the frame a , and on which is an adjusting thumb-nut, o' .

The operation of the apparatus is as follows: 30 The carbons being in contact, the electric current enters by the insulated post p on the arm n , and from thence to the bobbin of the axial magnet b through the plate e , standards $c' c'$, lever d , socket f , rod g , upper carbon, l , lower 35 carbou, m , arm n , and leaves by the post q , which is in metallic contact with arm n . The core e becomes instantly magnetized, and by induction attracts the small armature i , thereby clamping the rod g in the socket f of the lever d , the carbons being separated and the 40 electric arc formed between their ends by the core e' being drawn within the coil of the axial magnet b , opposed to which action is the tension of the spring o , which is adjusted to the current used, and the spring k is also set or 45 adjusted so as to draw the armature i away from the core e' sufficiently to release the rod g as soon as the current is reduced by an increase in the length of the arc, and it is found that 50 the current is reduced sufficiently to allow the armature to act by an almost imperceptible variation of the arc, so that the carbons are apparently feeding together with one continuous steady motion as fast as they are consumed, and that, too, without any very fine 55 adjustment of the regulating-springs, so that the apparatus adapts itself to currents of varying strength without any sudden changes in the light, thus enabling me, by this application of the principle of a clamping independent small armature with the core of an axial

65 magnet or other moving piece of magnetized metal, to make a reliable electric-lighting apparatus of very simple and cheap construction.

The lower carbon is shown in a fixed position, so that as it is consumed the light will gradually descend. Where it is required to keep the light always in one position any of the well-known devices may be used to raise the lower carbon.

Having now described the nature of my invention and a manner in which it may be practically applied, I wish it understood that I do not confine myself to the particular embodiment of it set forth; but 75

What I claim, and desire to secure by Letters Patent, is—

1. In an electric-lighting apparatus, the combination of a small armature with the core of 80 an axial magnet or other moving piece of magnetized metal, and feeding device for forming and maintaining an electric arc between the ends of carbon rods, substantially in the manner hereinbefore set forth.

2. In an electric-lighting apparatus, in combination, the coil e' of an axial magnet, lever d , and rod g , with a clamp or brake for holding the rod g to the lever d , and operated by magnetic induction from the core e' , substantially as hereinbefore set forth.

3. In combination, the lever d , rod g , bell-crank lever h , and spring k , substantially as hereinbefore set forth.

4. In combination, the core e' , the lever d , 95 and rod g , with the bell-crank lever h , provided with the armature i , substantially as hereinbefore set forth.

5. In an electric-lighting apparatus, the core e' of the axial magnet b , connected to and operating the carbon rod substantially in the manner described, in combination with the armature i , arranged to be attracted by the core e' , and apply a clamp or brake to arrest the feeding forward of the carbon rod, substantially as hereinbefore set forth.

6. In an electric-lighting apparatus, in combination, the core e' , the lever d , the rod g , the spring o , the bell-crank lever h , the armature i , and the spring k , substantially as and for 110 the purpose hereinbefore set forth.

7. In combination, the core e' of the axial magnet, the lever d , provided with a socket, f , the bell-crank lever h , and the armature i , adjustably connected to the lever h , substantially as and for the purpose hereinbefore set forth.

In testimony whereof I have hereunto set my hand this 19th day of May, A. D. 1880.

ALFRED G. HOLCOMBE.
